UNITED STATES PATENT OFFICE

ANKER S. LYHNE, OF BRIDGEPORT, CONNECTICUT

LIP-STICK HOLDER

Application filed December 20, 1929. Serial No. 415,416.

This invention relates to a holder or container for a lipstick, eyebrow pencil and the like, of the type in which the stick of cosmetic or the like is supported in a carrier and is moved from the enclosing casing to expose the stick for use and then withdrawn into the casing, and it is an object of the invention to provide an improved means for so shifting the stick.

10 It is also an object of the invention to provide a device of this character which may be operated with one hand to shift the stick and its carrier.

15 It is another object of the invention to provide a construction of this type of device in which when not in use the adjusting means for the carrier and the stick is entirely enclosed and inaccessible for accidental operation.

20 It is still another object of the invention to provide a carrier of this type in which there is no sharp edge at the end where the cosmetic is exposed to either cut the lips of the user or to scrape the sides of the stick should it 25 not be true or properly centered in the holder.

It is still another object of the invention to provide a construction which may be so held in use that the stick can not be pushed back into the holder by a pressure against 30 the object upon which it is being used.

With the foregoing and other objects in view, the invention consists in certain novel features of construction, combinations and arrangements of parts as will be more fully 35 disclosed in connection with the accompanying drawing.

In this drawing:

Fig. 1 is a partial side elevation and partial longitudinal section of a container involving my improved construction.

Fig. 2 is a transverse section substantially on line 2—2 of Fig. 1.

Fig. 3 is a side elevation of the stationary cam sleeve and the rotary cam sleeve removed from the casing.

Fig. 4 is a side elevation of the rotary sleeve with a portion of the upper end broken away to more clearly show the construction.

Fig. 5 is a side elevation of the stationary sleeve.

Fig. 6 is a side elevation of a container similar to that of Fig. 1, but showing the use of a slightly different type of closure.

Fig. 7 is a partial side elevation and partial section of a container showing a different closure.

Fig. 8 is a side elevation of a container using a hinge closure, which closure is shown in section.

Fig. 9 is a detailed section showing slightly different construction, and

Figs. 10 and 11 are detailed sections of the upper end of the device showing slightly different constructions.

In all the lipstick and similar containers of which I am aware at the present time the enclosed stick of cosmetic or the like is shifted in the casing to expose it at the open end thereof or withdraw it into the casing by means of a rotatable grip at the closed end of the casing. Thus, for convenient operation, it is necessary for the user to hold the casing in one hand while operating the rotary member to shift the stick with the other hand. Also, this rotary member is exposed so that while the container is being carried in a hand bag or the like, it is apt to be accidentally operated to crush or break the stick and thus make it unattractive, and also the loosened cosmetic gets into the movable elements interfering with proper operation and in addition because of the resultant messy appearance is very objectionable. I have overcome these objections by providing an improved container in which the rotary element or grip for shifting the cosmetic stick is located adjacent the open end of the casing so that when the container is held in the hand, this rotary grip may be held between the thumb and first finger of the same hand to adjust the position of the stick and also may be held firmly while in use to prevent pressure on the stick from forcing it back into the casing.

This also permits the use of a cap or closure for the open end of the casing which will enclose this grip and absolutely prevent accidental operation thereof while the container is closed or being carried in a hand bag or the like.

Referring first to Figs. 1 to 5 of the draw-

ing, the container comprises an outer shell or casing 11 which is closed at one end 12 and open at its opposite end. Carried within the casing is a member 13 which is held stationary in the casing. It is preferably in the form of a sleeve which is tight in the casing so as to be held by frictional engagement against turning in the casing. This stationary member carries a spiral cam shoulder, preferably in the form of a slot or groove 14. Mounted for rotary movement within this member 13 is a sleeve 15 having a longitudinal cam shoulder, preferably formed by a slot 16. This sleeve is provided with spaced peripheral beads or ribs 17 and 18 in which the member 13 is located and which will properly locate the two members 13 and 15 in correct relation to each other. The lower end of the member or sleeve 15 may be open or closed, but in the present construction is shown open. At its upper end it is rolled outwardly over the open end 19 of the casing 11 as shown in Fig. 1 and extended down on the outside thereof as shown at 20 so as to enclose this open end. Within the rotary sleeve 15 is a carrier 21 for a lipstick or other similar article 22, the carrier 21 being preferably in the form of a cup or sleeve open at its upper end to receive the stick 22, and also preferably having an opening 23 in its lower end although the use of this opening is optional. This carrier is slideable longitudinally in the rotary sleeve 15 which movement is secured by coaction of the shoulders on opposite sides of the slots 14 and 16 on a lateral projection or lug carried by carrier 21. This lug is preferably in the form of a transverse pin 24 forced through an opening in the side of the carrier and having a projecting end 25 extending into the slots 14 and 16. It will thus be evident that on rotation of the member 15 the carrier 24 will be rotated and the projecting end of the pin will move along the slot 15, thus shifting the carrier and the stick 22 longitudinally of the device to project its free end from the open end of the casing or to retract it into the casing as desired. It will, of course, be understood that as it is relative turning movements between the members 13 and 15 which shifts the carrier, the same effect will be secured if the slots 14 and 16 are reversed. That is, if the spiral slot is in the rotary member and the longitudinal slot is in the stationary member.

It will be evident from an inspection of the drawing that the folded over upper end 20 of the sleeve 15 forms a smooth rounded edge 26 at the end of the casing which covers the sharp edge of the casing and provides a smooth round end which can not cut or injure the lips. It also effectively eliminates any sharp edge which could cut or scrape the stick 22 as it is shifted outwardly or inwardly should the stick not be properly centered,

and thus prevents the cosmetic being scraped off which would get into the movable elements and prevent their proper functioning, or to make the device messy and unattractive. To hold the rotary sleeve 15 with sufficient pressure to prevent its too easy movement and also to give more uniform operation, the member 13 may be provided with one or more spring lugs 27 to frictionally engage the outer surface of the sleeve 15 and give sufficient resistance to its turning to normally hold it in adjusted position, but still permit easy manipulation thereof.

It will be evident from the foregoing description that the folded over end 20 of the sleeve 15 provides a band or grip adjacent the open end of the casing which is accessible on the outside of the casing and, therefore, by merely gripping this band and rotating the sleeve 15, the stick 22 may be adjusted as desired. This permits the use of an outer casing which is entirely closed at its lower end, and also permits the easy adjustment of the stick 22 with one hand while the device is being used. Thus, the operator may grip the sides of the casing in her hand and then by means of the thumb and first finger may grip the band 20 and rotate the sleeve 15 to adjust the stick 22 as desired. In the same manner, the band 20 may be held between the thumb and first finger while the device is in use to prevent the sleeve 15 turning and thus prevent longitudinal pressure on the end of the stick 22 forcing it back into the casing.

The open end of the device may be enclosed by a suitable cap or closure 28. It is preferred to provide on the outer surface of the casing 11 a band 29 which may be formed by rolling the band into the casing as shown in Fig. 1 or by soldering onto the surface of the casing a separate ring as shown at 30 in Fig. 9. This band is of a somewhat larger diameter than the grip 20 as shown in Fig. 1 and the cap or closure 28 is of a size to tightly grip the band 29. Thus, when the cap 28 is applied as shown in Fig. 1 it loosely encloses grip 20 but tightly grips the band 29 and is thus effectively held in closed position on the casing. As the closure is loose on the grip 20, turning movements of the cap in applying or removing it will not turn the sleeve 15 to shift the stick 22. Also as shown in Fig. 1, as the cap 28 encloses the grip 20, this grip is entirely inaccessible when the closure is in position, thus effectively preventing accidental shifting of the stick 22 while being carried in a bag or otherwise. The casing is preferably provided with a band 31 adjacent its closed end similar to the band 29 so that when the cap or closure 28 is removed, it may be slipped over the closed end of the casing onto the band 31 as indicated in dotted lines, Fig. 1. This effectively prevents losing or misplacing of the cap.

while the device is in use, and this cap may be made of any length desired to give the appearance desired or to give a long grip to facilitate holding the device in the hand while in use.

Such a construction is shown more clearly in Fig. 7 in which the band 32, corresponding to the band 29, is moved to a position lower on or adjacent the closed end of the casing, and the cap or closure 33 is made of sufficient length to enclose practically the entire casing. In use the cap is removed and placed over the closed end of the casing as indicated in dotted lines and as the cap is long, it gives the effect of a long casing to improve the grip of the hand while in use, but when the holder is closed, as shown in full lines, the total length of the device is no longer than the casing itself. The bands 32 and 34 corresponding to the bands 29 and 31 in Fig. 1 may be formed in the same manner as shown in Fig. 1 or Fig. 9, but in Fig. 7 are shown as being on a cap 35 embracing the closed end of the casing, and are separated by bead 36 to form a stop to engage the edge of the cap and limit the distance it may be forced onto the casing.

In Fig. 6 is shown a device in which the cap or closure 37 is made somewhat shorter and also of somewhat smaller diameter so as to grip the band 20 instead of the band 29. The other constructions are, however, preferred as this construction permits the turning of the sleeve when the container is closed. In this arrangement, the band 38, adjacent the opposite end of the casing, would be the same size as the band 20 so that cap 37 may be placed thereon as shown in dotted lines while the device is in use.

In Fig. 8, the cap 37 is permanently held on the casing by means of a hinge 39, this hinge being secured to the band 29. This effectively permanently secures the cap to the casing and prevents it from being lost. In either of the forms shown in Figs. 1, 6 or 8 a separate and additional cap may be applied over the closed end of the casing. This cap is shown at 40 in Fig. 8, and is of the same contour and appearance as the closure cap 28 or 37 used at the opposite ends of the device. This cap may be used to secure an improved appearance and effect and is intended principally for ornamentation, although it does, of course, provide an improved grip and also an extra closure.

It is not necessary that the end of the sleeve 15 be folded over on the outside of the end of the casing 11. It may be merely folded upon itself and be in alignment with the end of the casing as shown at 35 in Fig. 10, or there may be a separate band secured adjacent the end of the sleeve as indicated at 41, Fig. 11. In either case, however, a grip is provided adjacent the open end of the casing and accessible on the outside thereof by means

of which the sleeve 15 may be rotated. These grips are also enclosed by the closure caps the same as is the other forms, and in the form shown in Fig. 10 it also provides a rounded edge to prevent injury while in use.

An additional advantage of this construction of holder is that the outer surfaces can be very effectively ornamented in a large number of different ways and to give a large variety of different effects, so that it can be made very attractive in appearance.

Having thus set forth the nature of my invention, what I claim is:

1. In a lipstick container, an outer casing, a stationary sleeve in the casing, a rotary sleeve embraced by the stationary sleeve, one of said sleeves having a longitudinal slot and the other a spiral slot and a longitudinally movable cosmetic carrier in said rotary sleeve carrying a lateral projection in said slots, said rotary sleeve being open at its upper end for protrusion of a cosmetic stick carried by the carrier and provided with means at said open end accessible outside the casing by which said sleeve may be rotated to shift the carrier.

2. In a lipstick container, an outer casing, a stationary sleeve in the casing having a spiral guideway, a rotary sleeve in the stationary sleeve having a longitudinal slot, and a cosmetic carrier in the rotary sleeve having a lateral projection in said slot and guideway, said rotary sleeve being open at its upper end for protrusion of a cosmetic stick carried by said carrier and provided with a band at said open end forming a grip to rotate said sleeve to shift the carrier.

3. In a container of the character described, an outer casing closed at its lower end and open at its upper end, a stationary sleeve in said casing, a rotary sleeve embraced by the stationary sleeve, one of said sleeves having a longitudinal slot and the other a spiral slot, and a longitudinally movable carrier in said rotary sleeve carrying a lateral projection in said slots, said rotary sleeve being open at its upper end for protrusion of the element carried by the carrier and extending outwardly over the open end of the casing to provide a grip for rotating said sleeve to shift the carrier.

4. In a holder of the character described, an outer casing, a stationary member and a rotary sleeve member in said casing, one of said members having a longitudinal guiding shoulder and the other a spiral shoulder, a longitudinally movable carrier in said sleeve and a lateral projection on said carrier cooperating with said shoulders, said sleeve being open at one end for protrusion of the element carried by the carrier and provided with a grip adjacent said end accessible outside the casing by which said sleeve may be rotated to shift the carrier.

5. In a lipstick container, an outer casing

open at one end, a stationary sleeve and a rotary sleeve in the casing, one of said sleeves having a longitudinal shoulder and the other a spiral shoulder and a longitudinally movable cosmetic carrier in the rotary sleeve having a lateral projection cooperating with said shoulders, said rotary sleeve being open at the open end of the casing and folded outwardly over and on the outside of the end of the casing to provide a grip by which the sleeve may be rotated.

6. In a lipstick container, an outer casing open at one end, a stationary sleeve and a rotary sleeve in the casing, one of said sleeves having a longitudinal shoulder and the other a spiral shoulder, a longitudinally movable carrier in the rotary sleeve having a lateral projection cooperating with said shoulders, said rotary sleeve being open at the open end of the casing and provided with a grip outside the casing adjacent said end by which the sleeve may be rotated, an enlargement on the outer wall of the casing below said grip and of a somewhat greater diameter than the grip, and a closure for the open end of the casing embracing said enlargement.

7. In a lipstick container, an outer casing open at one end, a stationary sleeve and a rotary sleeve in the casing, one of said sleeves having a longitudinal slot and the other a spiral slot, a longitudinally movable carrier in the rotary sleeve having a lateral projection in said slots, said rotary sleeve being open at its outer end and folded outwardly over the open end of the casing to form a grip outside the casing, an enlargement on the outer wall of the casing below said grip and of somewhat greater diameter, and a closure for the casing embracing said enlargement.

8. In a lipstick container, a casing open at one end, a rotary sleeve in said casing also open at said end, a carrier longitudinally movable in said sleeve, means for shifting the carrier by turning movements of the sleeve, and a grip on the sleeve adjacent the open end thereof outside the casing by which the sleeve may be rotated.

9. In a lipstick container, a casing open at one end, a rotary sleeve in said casing also open at said end, a carrier longitudinally movable in said sleeve, means for shifting the carrier by turning movements of the sleeve, a grip on the sleeve outside the casing adjacent the open end thereof whereby the sleeve may be rotated, an enlargement on the casing below the grip and of somewhat greater diameter than the grip, and a closure cap for the open end of the casing embracing said enlargement.

10. In a lipstick container, a casing open at one end, a rotary sleeve in said casing also open at said end, a carrier longitudinally movable in said sleeve, means for shifting the carrier by turning movements of the sleeve, a grip on the sleeve outside the casing

adjacent the open end thereof whereby the sleeve may be rotated, an enlargement on the casing below the grip and of somewhat greater diameter than the grip, a similar enlargement adjacent the closed end of the casing, and a closure cap for the open end of the casing of a size to fit both said enlargements.

In testimony whereof I affix my signature.
